UNITED STATES PATENT OFFICE.

JOHN OSCAR NORRIS, OF PITTSBURG, KANSAS.

SAFETY LEVER SWITCH LOCK.

Application filed May 23, 1921. Serial No. 471,823.

To all whom it may concern:

Be it known that I, JOHN OSCAR NORRIS, a citizen of the United States, and resident of Pittsburg, county of Crawford, State of Kansas, have invented a certain new and useful Improvement in Safety Lever Switch Locks, of which the following is a complete specification.

This invention relates to switch stand locks and has for its object to produce a lock of such construction that the key cannot be withdrawn from the lock until the switch lever has been thrown into such a position that there is no chance of the switch point slightly springing open and forming a space for the entry of the flange of a wheel and thus lead to the splitting of the switch and the derailment of the train.

Another object is to produce a lock of such a character that it will be efficiently protected from the elements and which, however, may be easily withdrawn from its casing for oiling and inspection purposes.

With these objects in view the invention consists in certain novel and useful features of construction and organization of parts as hereinafter described and claimed; and in order that it may be fully understood, reference is to be had to the accompanying drawings, in which:

Figure 1 is a top plan view of a switch stand equipped with the locking mechanism of the invention.

Figure 2 is a section on the line II—II of Figure 1.

Figure 3 is a section taken on the line III—III of Figure 4, and illustrates the locking mechanism in locked position.

Figure 4 is a section taken on the line IV—IV of Figure 3.

Figure 5 is an enlarged section similar to Figure 3, but illustrates the locking mechanism in unlocked position.

Figure 6 is a section on the line VI—VI of Figure 5.

Figure 7 is a section on the line VII—VII of Figure 3.

Figure 8 is a section on the line VIII—VIII of Figure 5.

Figure 9 is a section on the line IX—IX of Figure 7.

In the said drawings, where like reference characters identify corresponding parts in all of the Figures, 1 is the table support of a switch stand, 2 the switch op-

erating rod, 3 the connection securing the rod 2 to the lower end of the pivot 4 which passes through the table 1 and extends vertically above said table, all of said parts 60 being of ordinary form and construction.

Pinned or otherwise secured to the pivot 4 is a collar 5, adapted to hold in position and bear upon an operating frame of some- 65

what different form than the ordinary op- erating frame, but possessing the same mode of operation. Carried by the frame 6 is an operating switch lever 7, pivoted as at 8 as is customary. When operating 70

the switch, the lever is horizontal, with its upper end in engagement with a channel 6^a formed in member 6 as customary, and resting flatwise on the table. After use, 75

and in order to lock the switch against movement, switch lever 7 is swung to a vertical position for engagement with one of a pair 80

of notches 9 in the periphery of the table, as customary. A pair of stops 10 are formed on the upper surface of the table to come into abutment with the side edges 85

of frame 6 and prevent the frame from being swung past the point where the switch lever will engage a notch 9.

Frame 6 is of somewhat greater width to one side of its pivotal point than to the other, and formed integrally with or secured thereto is a lock casing 11 as shown in the drawing, or of any suitable or preferred form, which will have one side wall coincident with the adjacent edge of the frame 6 and the other wall coincident with the channel 6^a thereof.

The upper surface of casing 11 is parallel with the table and this casing near its face is formed with a recess or pocket for 95

the reception of a lock mechanism 12 provided exteriorly with a ring 13 by which it can be lifted out of the recess as will hereinafter appear. On the opposite side of channel 6^a from casing 11, is a vertical 100

wall 14 and bridging the channel 6^a and formed integrally with members 11 and 14 is a bridge portion 15, it being understood that the front wall of casing 11 will be extended across and connected to wall 14 105

and will be formed with a slot 15^a to accommodate lever 7 and its pivot (see Figure 2). The parts just described will form a housing for the upper end of switch lever 7 when said lever occupies its vertical position as will be readily understood.

The frame of lock 12 is formed of a top,

web and bottom, the former comprising a top member 16 formed with an extension portion 16^a, and a flange which is adapted for abutment on a gasket 17 fitted within the flanged opening in the top of casing 11. Depending downwardly from top 16 is the web 18 of suitable thickness and equal in width to the width of the recess in member 11, as will be seen by reference to the drawings. Formed integrally with the web 18 is a bottom portion 19 adapted to rest on the bottom of the recess and of substantially the same dimensions. To secure the lock frame in position, it is engaged by a screw 20 fitted in a bore 21 formed in casing 11, and adapted to hold the lock against withdrawal from casing 11.

A bolt 22 is carried by the frame lock 12 and when in withdrawn position is adapted to have its front end substantially flush with the inner wall of casing 11 in alignment with channel 6^a (see Figure 6), and when in locked or projected position engages a bolt opening 23 formed in the upper end of the switch lever. It will be noted by reference to Figures 2 and 5, that in order to provide for the accommodation of the bolt 22, casing 11 is provided with a slot 11^a in the upper part of its wall abutting channel 6^a, and that the extension 16^a of the lock casting is formed on member 16 in order to close the slot 11^a at its upper end.

Bolt 22 has sliding engagement with web 18 near its upper end and fits between said web and a flange 24 depending from top 16 and formed with a shoulder 25 upon which the bolt is adapted to rest. Connecting the lower end of flange 24 to web 18 are closure members 26 forming a slot 27 between them and leaving the bottom face of the bolt exposed for the greater part of its length. Extending through the slot just described and engaging a slot 30 formed in bolt 22 is a lever 28, pivoted about midway its length on a pivot pin 29 secured to web 18 of the lock frame.

The opposite end of lever 28 passes between a pair of guide arms 31 secured to web 18 and fitted between said arms and secured to the web 18 is an expansion spring 32 adapted to press against the end of lever 28 and force its operating face 33, formed at its end with a notch 34, into continuous engagement with a key operated cylinder 35, journaled on a pin 35^a secured to web 18 and formed with a cam face 35^b for acting on the operating face 33 of lever 28. The cylinder 35 also carries a cam 36 which when turned will operate a catch 37, pivoted at 38 to web 18 and against the back face of which an expansion spring 39, fitted in a recess in member 19, is adapted to press. The catch is formed with an operating face 40 and a notch 41 for a purpose which will herein-
65 after appear.

In order to provide means whereby the operating key K may be held within the lock until the switch lever 7 has been moved to vertical position, a bell crank lever 42 is pivoted on a rod 43 passing through frame members 19 and 18, and is thus held in a groove 44 formed on the face of web 18 (see Figure 4).

The bell crank lever 42 is formed at one end with an operating arm 45 which fits within the housing formed by members 14, 15 and 11 and against which the face of the upper end of the switch lever is adapted to abut when in vertical position (see Figure 7). The opposite end of the lever 42 is adapted to be yieldingly advanced when arm 45 is free for movement by an expansion spring 46 secured in groove 44 and the end of said lever is formed with a pin 47 adapted to be projected into an opening 48 formed in the rear end of cylinder 35 under certain conditions.

The operation of the device is as follows: Referring to Figures 3 and 7, it will be noted that the switch lever is in locked position with the bolt engaging the upper end of the switch lever and the bolt operating mechanism in position for the reception of a key, the face of the switch lever 7 being in abutting relation with arm 45 of the bell crank lever 42 and holding the pin 47 thereof withdrawn as shown in Figure 7. The key K is now inserted into the opening 35^c in the face of casing 11 and as it is turned will impart movement to cylinder 35, and cam 36 thereof will force catch 37 downward by its engagement with the face 40 thereof (see Figure 9). The continued operation of the key will cause the cam 36 to operate lever 28 by contact with its face 33 and by the time said cam comes in engagement with and is held from further movement by notch 34, the lever 28 will have withdrawn the bolt from engagement with the bolt opening of switch lever 7 (Figures 5 and 6). The switch lever will now be grasped and pulled upwardly until it occupies its horizontal position when it will be free for horizontal turning movement on the table in order to throw the switch points, and immediately the upper end of said lever ceases to press against the end 45 of bell crank lever 42, said lever will automatically through the action of its spring 46, project its pin 47 into the opening 48 formed in the rear face of cylinder 35, and the parts will occupy the position shown in Figure 5, thus locking the parts from further movement and holding the key in such a position that it cannot be withdrawn from opening 35^c, as it will come into contact with the inner face of the wall of the recess in casing 11. The key, therefore, cannot be withdrawn until the switch lever 7 has again been swung to a vertical position with its face in abut- 130

ment with the arm of the bell crank lever, to withdraw the pin thereof from engagement with cylinder 35, as will be readily understood.

5 It will be readily apparent that it will only be necessary to withdraw bolt 22 from bolt openings 23 and then remove screw 20 in order to lift the entire lock 12 from its recess, for oiling or inspection purposes.

10 It will be apparent that I have produced a switch lock of such character that the operator cannot throw the switch and carelessly leave it in such a condition that there is danger of a car splitting the switch, unless the operator leaves his key in the lock, as the operations necessary to remove the key will set the switch and lock it in such a position that there is no chance of accidental opening movement of the switch 15 point.

20 From the above description it will be apparent that I have produced a device of the character described which possesses all of the features of advantage set forth as desirable, and while I have described and claimed the preferred embodiment of the same, I reserve the right to make all changes properly falling within the spirit and scope 25 of the appended claims.

30 I claim:

1. A switch lock, comprising a table provided with a pair of notches, a frame pivotally mounted on said table and provided with a channel, a switch lever pivoted to 35 said frame for movement in a vertical plane and adapted to engage one of the notches of the table when in a vertical position and the channel of the frame when in a horizontal position, a casing mounted on said 40 frame, and formed with a recess, a lock mechanism depending from the top of the casing into said recess and having a watertight joint therewith and adapted to lock the switch lever in its vertical position, and 45 means to prevent operation of said lock mechanism when it is in unlocked position and the switch lever is out of its vertical position.

2. A switch lock, comprising a table, a 50 frame pivotally mounted on said table for swinging movement, a switch lever pivoted to said frame for movement in a vertical

plane, a casing mounted on said frame and provided with a recess and forming a housing for the end of the switch lever when in a vertical position, a lock mechanism in the recess of said casing, and means for retaining the lock mechanism in position and inaccessible for removal when in locked position.

3. A switch lock, comprising a table, a frame pivotally mounted on said table for swinging movement, a switch lever pivoted to said frame for movement in a vertical plane, a casing mounted on said frame and provided with a recess, a lock frame secured in said recess, a bolt mounted for sliding movement in said lock frame, a key-operated member, a lever pivoted to said key frame, for yieldingly advancing said bolt 60 when the key-operated member is rotated in one direction and adapted when the key-operated member is rotated in the opposite direction to be reversely moved to withdraw the bolt, yieldingly-actuated means to 65 lock the key-operated member from movement when the switch lever is swung out of a vertical position, and means actuated by the switch lever when moved to vertical position, to unlock the key-operated member. 70

4. A switch lock comprising a table having edge notches, a frame pivotally mounted for horizontal swinging movement on the table, a switch lever mounted on the frame for movement in a vertical plane independent of the frame and into and out of the notches of the table, a bolt for locking the switch lever within any of said notches, a spring-actuated lever to advance the bolt, a spring-actuated lever to hold the first-named lever with the bolt advanced, rotary key-actuated means to trip said holding means and then operate the first-named spring-actuated lever to retract the bolt, and a yieldingly-actuated lever for preventing 80 rotation of the key-actuated means when the switch lever is withdrawn from a notch and adapted to be tripped by the latter from engagement with said key-actuated means.

90 In witness whereof I hereunto affix my signature.

JOHN OSCAR NORRIS.
